William P. McDermott,

By Victor J. Evans

Attorney

UNITED STATES PATENT OFFICE.

JOHN L. SEVERNS AND WILLIAM P. McDERMOTT, OF EAST ST. LOUIS, ILLINOIS.

CAR-DOOR.

No. 875,465.

Specification of Letters Patent.

Patented Dec. 31, 1907.

Application filed October 13, 1906. Serial No. 338,803.

To all whom it may concern:

Be it known that we, JOHN L. SEVERNS and WILLIAM P. McDERMOTT, citizens of the United States, residing at East St. Louis, in 5 the county of St. Clair and State of Illinois, have invented new and useful Improvements in Car-Doors, of which the following is a specification.

This invention relates to car doors more 10 particularly designed for use on freight cars, but capable for use in other relations.

One of the objects of our invention is to provide a horizontally sliding door having an opening therein, and a vertically sliding 15 closure for said opening.

Still another object is to provide a laterally sliding door with an opening to be closed by a vertical slide and to provide means for attaching a spout or chute in front 20 of said opening to discharge grain from the car.

Still another object of the invention is to provide a simple, strong and durable door for grain cars in which provision is made for 25 quickly attaching a spout to an opening in the door for discharging the contents of the car.

These and other objects are attained by 30 means of the construction illustrated in the drawings, in which:—

Figure 1 is a longitudinal sectional view, showing the door in elevation. Fig. 2 is a longitudinal sectional view on the line 2—2, Fig. 1. Fig. 3 is a vertical sectional view 35 on the line 3—3, Fig. 1. Fig. 4 is a front elevation of the door detached from the car. Fig. 5 is a detail perspective view of the discharge spout secured at each side of the 40 opening in the door. Fig. 6 is a detail section through the discharge spout and showing the manner in which the spout is detachably secured to the door. Fig. 7 is a detail section 45 through the door, showing the manner of mounting the cogged rollers for sliding the door laterally. Fig. 8 is a detail section showing the manner of securing the upper end of the stay rod in front of the door. Fig. 9 is a detail section, showing the pin for 50 holding the door closed.

Referring to the drawings for a more particular description of my invention, the numeral 1 designates the frame portion of a freight car of ordinary construction provided with door posts 2, 3. The post 2 is 55 slotted as at 4, and upon each side of said post is a metal wear-plate or brace 5 bolted

at its upper end to the upper portion of the car frame, as at 6, while the lower end is secured to a sill of the car. The post 3 is provided with similar wear-plates 7. The door 60 consists of a body portion 8 provided with vertical braces 9, said braces extending below the lower edge of the door, and journaled between the braces 9 are cogged rollers 10, said rollers adapted to engage a rack-bar 65 11 secured to the sill of the car. The door 8 is provided with a central vertical opening 12 and at the sides of said opening, metal guide strips 13 are provided between which a closure 14 is adapted to slide, said closure 70 having a ring 15 secured to a metal strap 16 extending upward from the closure. A stay bar 17, Fig. 3, is seated at its lower end within the sill as at 18, and the upper end of said stay bar is fitted to slide in a keeper-plate 19 75 secured underneath the longitudinal frame-piece 20 of the car, said keeper 19, provided with a slot in which the upper end of said stay-bar is seated. A winged nut 21 fits the threaded portion of the upper end of the 80 stay-rod and is adapted to be turned into contact with the keeper 19 to hold said rod in position, said rod passing through the ring 15 to hold the door closed. A handle 22 is secured to one end of the door and a locking 85 pin 23, shown in detail in Fig. 9, passes through the door and through the post 3 to hold the door closed, said locking pin being suspended from a chain 24 secured to the outer portion of the car. Secured to one 90 edge of the door is a guard-strip 25, said guard strip extending longitudinally of the car and sliding between keepers 26 on the sill. The purpose of the guard-strip is to prevent the grain from clogging the rack-bar 95 11 when the door is moved laterally to its open position. A diagonally disposed post 27 is provided with wear-plates 28 and is slotted at 29 to brace the door in its open position when moved laterally on the rack-bar 11. A removable discharge spout 30 is provided with hook bars 31 having backwardly extending hooks 32 which engage slots 33 in the guide strips 13, said spout having an inclined bottom 34 to discharge 100 the grain when the closure 14 is open and said spout being detachably secured in front of said opening.

From the foregoing, the construction and operation of our car door will be readily 110 understood and may be briefly described as follows. When it is desired to discharge the

contents of the grain car, the spout 30 is secured in place and the closure 14 is raised, thus permitting the grain to pass out by gravity through the opening and over the 5 spout. When the grain has been discharged to a level below the closure 14, the door 8 may be moved laterally upon the rack-bar 11 and the remaining contents of the car removed through the door opening.

10 From the foregoing, it will be obvious that that a car door made in accordance with our invention will be strong and durable, will permit the attachment and detachment of a discharge spout and can be shifted laterally to provide a large opening for the discharge of the contents of the car.

15 Having thus described the invention, what is claimed as new, is:—

1. A car door provided with an opening 20 at the central lower portion thereof, guide strips secured to the door at opposite sides of said opening, a vertically sliding closure fitted to slide in the guide strips, a metal strap secured to said closure, a ring connected to said strap, a stay bar on which said ring slides, said stay bar being seated at its lower end in the car sill and its upper end being detachably fitted into a slotted keeper plate and provided with a winged nut, said 25 30 guide strips provided with oppositely disposed slots, and a detachable spout provided

with bars secured to the sides thereof, said bars having downwardly extending hooks upon their inner ends to engage said slots, substantially as described.

35 2. A sliding car door provided with an opening in the lower side and centrally of said door, guide strips secured at opposite sides of said opening, a vertically sliding closure for said opening, said closure being 40 fitted into the guide strips, a metal strap extended upward from said closure, said strap carrying a ring, a stay bar upon which said ring slides, said stay bar being seated at its lower end in the car sill and its upper end 45 being detachably fitted into a slotted keeper plate and provided with a winged nut, said guide strips being provided with slots, one at each side of each opening, and a removable spout provided with bars secured to the sides 50 thereof, said bars having downwardly extending hooks at their inner ends to engage said slots, and means for holding the sliding door from movement, substantially as described.

55 In testimony whereof, we affix our signatures in presence of two witnesses.

JOHN L. SEVERNS,
WILLIAM P. McDERMOTT.
